(57) **CLAIM**

The ornamental design for a rifle scope, as shown and described.

DESCRIPTION

FIG. 1 is a perspective view of the rifle scope of our new design;

FIG. 2 is a top plan view of said rifle scope of FIG. 1;

FIG. 3 is a bottom plan view of said rifle scope of FIG. 1;

FIG. 4 is a left side elevation view of said rifle scope of FIG. 1;

FIG. 5 is a right side elevation view of said rifle scope of FIG. 1;

FIG. 6 is a front elevation view of said rifle scope of FIG. 1; and,

FIG. 7 is a rear elevation view of said rifle scope of FIG. 1.

The broken lines in FIGS. 1 and 6 are included for the purpose of illustrating a portion of the rifle scope that forms no part of the claimed design.

1 Claim, 4 Drawing Sheets
